UNITED STATES PATENT OFFICE.

HENRY HUNT, OF GREENVILLE, NEW JERSEY, ASSIGNOR TO THE HARTFORD CARPET COMPANY, OF HARTFORD, CONNECTICUT.

DESIGN FOR A CARPET.

SPECIFICATION forming part of Design No. 12,828, dated March 21, 1862.

Application filed February 11, 1862. Term of patent 3½ years.

To all whom it may concern:

Be it known that I, HENRY HUNT, of Greenville, in the county of Hudson and State of New Jersey, have invented a new and original 5 Design for Carpets, of which the following is a specification.

This invention relates to a new and original design for carpets and similar fabrics; and it consists in the novel grouping and configuration of figures hereinafter more fully described.

The accompanying photograph illustrates a face view of a carpet having my new design.

A is a leaf group with projecting buds. B is a leaf cluster set on the same stem with A. 15 From B projects on one side the drooping flower C, with projecting stamens, and on the other the open bulb-like flower D, with stamens. From B projects upward a forking stem bearing on one branch the group E, consisting of a bulb-like flower with projecting blossoms and leaves, and on the other branch the large fan-shaped flower figure F with prominent stamens. From F projects a stem bearing leaves and blossoms, and forking at the 20 circular flower G, bearing on one branch the group H, consisting of a bell-shaped stamened flower and surrounding leaves, sprays, and blossoms, and on the other branch the flower K, with its stamens and the star flower-and-leaf 25 group L. From F also projects another stem bearing the group M, consisting of leaves and blossoms. From M a stem projects and bears the stamened blossom -and -flower group N.

Another stem from M bears on one fork the leaf-and-bud cluster O, and on the other the 35 flower-and-leaf group P. These figures from A to P present the appearance of being all arranged along an S-shaped vine, branch, or stem, S, forking above.

Q is an open flower figure with drooping 40 buds at the left. R (shown partly at one end of the design and partly at the other) is a serrated flower resembling a cactus blossom. T is a flower, leaf, and bud group. The figures Q, R, and T are arranged along the same vine, 45 branch, or stem U, which bears in addition flag-like leaves and bud sprays, as shown.

It is characteristic of the flowers on the stem S that their stamens are prominent, while in those on the stem U they are not shown. 50

These figures are all arranged upon a background, V, ornamented by small figures that resemble interlocking arches.

I claim—

1. The design for carpets, consisting of the 55 figures A B C D E F G H K L M N O P Q R T and stems S and U, with connected parts, substantially as shown.

2. The design for carpets, consisting of the figures A B C D E F G H K L M N O P Q R 60 T, stems S and U, with connected parts, and ground V, substantially as shown.

HENRY HUNT.
